DISTILLATION OF TAR

Stuart Parmelec Miller, Englewood, N. J., assignor to The Barrett Company, New York, N. Y., a Corporation of New Jersey

Application March 23, 1928. Serial No. 263,989

3 Claims. (Cl. 202—30)

This invention relates to improvements in the distillation of tar, tar oils and pitches and includes a new method of distillation as well as an improved apparatus therefor. Although the invention is applicable to the distillation of tar with gases from other coal carbonization and gasification operations, it will be described more particularly as applied to coke oven operations.

In the ordinary operation of by-product coke ovens, the gases produced by the coking operation pass from the individual ovens through uptake pipes and goose-necks to a collector main common to the ovens of the battery. The gases, commonly known as "foul" gases, leave the ovens at high temperatures, for example at 600° to 700° C., or higher, and carry a considerable proportion of pitchy material, tars and oils as well as solid particles of coke, dust, etc. Ordinarily, the gases are cooled by the application of sprays 20 of ammonia liquor or ammonia liquor and tar in the collector main, or by circulating ammonia liquor and tar through the main, the heat in the gases being thereby dissipated and lost. The cooling causes separation of tar containing heavier oils in the collector main. Further cooling is effected in the cross-over main which connects the collector main to the condensing system and an additional quantity of tar carrying both heavy 25 and lighter oils is thus separated. In the coolers or condensers tarry oils are separated. The tars and tarry oils are blended and are ordinarily shipped from the coke oven or other coal distillation plant to a tar distillation plant for distillation and separation of the oils, and the production of pitches of varying quality. Handling costs, freight charges and distillation cost, including fuel, capital and maintenance expense for the special equipment required for distillation, add to the cost of the tar distillation 30 products.

The present invention provides an improved method and apparatus in which tar, tar oil or pitch is distilled by means of hot gases from coal gasification or carbonization operations, which gases have been cleaned at the required temperature by a scrubbing treatment. The present invention makes use of heat contained in high temperature coal carbonization gases, such as gases 35 from the collector main of a coke oven battery, by employing them for distilling tar, tar oil or pitch while they are still at a high temperature and after they have been subjected to a cleaning operation.

The cleaning of the gases at a high temperature

serves to remove therefrom to a greater or less extent the entrained tar and pitch constituents, leaving relatively clean gases at a high temperature for use in the distillation. When these relatively clean and still hot gases are so employed 60 for distillation, the distillate from the still, which is admixed with the gases employed for the distillation, and which is subsequently recovered therefrom by cooling and condensation, will be a relatively clean distillate, i. e., relatively free 65 from the heavy tar and pitch constituents initially entrained in the gases.

The cleaning of the hot coal distillation gases according to the present invention is carried out at the required temperature and without reduction of temperature of the gases cleaned below that at which they are to be used for subsequent distillation. This scrubbing of the gases may be effected with or without distillation of the scrubbing medium. The scrubbing medium may be 70 preheated to a temperature approaching that of the gases scrubbed or it may be at a lower temperature. The scrubbing operation should be sufficiently complete to remove from the gases 75 completely or to the desired extent the entrained pitch or tar constituents, leaving the gases still at the required temperature. Counter-current scrubbers which bring about intimate contact of the gases with the scrubbing liquid can be employed. The scrubbing liquid may advantageously be all or a portion of the hot tar or pitch 80 produced by subsequent distillation of the gases after they have been cleaned, thereby obtaining a counter-current scrubbing of the gases and distillation of the tar, if desired; other materials 85 may likewise be used as scrubbing media.

The material to be distilled according to the present invention may be coal tar produced at coke oven plants, or gas house tar produced at 90 gas retort plants (vertical, horizontal or inclined), water gas tar, or tar from another source. Such tars frequently contain a considerable percentage of water intimately admixed or combined therewith, particularly where water or ammonia 95 liquor is employed for separating and condensing the tar constituents from the coal distillation or other gases, and such tars may, if desired, be dehydrated before being distilled according to this invention.

The gases which are employed, according to the present invention, for distillation are hot gases produced by a coal carbonization or gasification operation, and which are cleaned or partially cleaned prior to use for distillation. The 100 hot gases, which are subjected to cleaning and

then used for distillation, may be hot coke oven gases or hot retort gases or hot water gas, etc. In the case of coke oven gases, for example, the gases escape from the coke ovens at a high temperature, e. g., from 600° to 700° C. or even higher in some case, and can be cleaned at a temperature sufficiently high to permit effective distillation therewith after cleaning. High temperature gases are also formed and are withdrawn from gas retorts, water gas retorts, producers, etc. and can be used for distilling after cleaning.

Coal carbonization gases when they leave the ovens or retorts, etc. in which they are formed contain entrained solid and liquid impurities which it is the object of the scrubbing treatment to remove to a greater or less extent. If the scrubbing medium employed is of approximately the same temperature and composition as the entrained liquid impurities, which it is desired to remove, the scrubbing will be effected without material alteration of the scrubbing medium or of the gases treated, except by removing from the gases and adding to the scrubbing medium the entrained particles removed from the gases by the scrubbing operation. If the scrubbing medium is colder than the gases treated, the gases will be cooled and condensable constituents will be thrown out of the gases and removed from the system with the residue from the scrubber, while the scrubbing medium will be heated and if low boiling constituents be present in this medium they may be volatilized and carried over with the gases to the still. If the scrubbing medium utilized is at a temperature higher than the temperature of the gases, the gases may be heated and partial volatilization of entrained liquid impurities may result although if the scrubbing medium contains material which will be volatilized by the hot gases no increase in temperature of gases may result due to expenditure of heat as latent heat of vaporization of the material evaporated.

Although in a general way the entrained liquid impurities are in equilibrium with the gases, these impurities which are carried forward from the ovens, retorts, etc., are present as fine globules in the form of a mist. Prolonged contact of these entrained globules with the hot gases would bring about a condition of equilibrium between the gases and the composition of the globules, but it is the object of this invention to scrub the gases at a high temperature, preferably as quickly as possible after the gases leave the coal carbonization apparatus, and equilibrium conditions may not be established in so short a time.

Tar, preferably heavy tar, or pitch, preheated where practical, is well adapted for use in scrubbing the gases in carrying out the invention.

In order to avoid unnecessary cooling of the gases and consequent condensation of vapors carried by the gases and loss in the amount of heat available in the gases for distillation purposes, the equipment through which the gases pass on the way from the coal carbonization or gasification apparatus to the still as well as the still itself, may advantageously be insulated, and the distance between the coal carbonization apparatus and the scrubber on the one hand, and the scrubber and the still on the other, kept at the minimum which practical operation permits. In many cases, particularly when hard pitches are to be made or high boiling oils to be distilled, gases should be used at high temperatures. In such a case the gases will be subjected to little, if any, spraying in the collector main, and all

equipment through which the gases pass to the still will be well insulated.

Although the invention is of broader application, it will be described more particularly in connection with coke oven operation. The gas employed for the distillation may be cleaned at a temperature not greatly below that at which it leaves the coke oven, or the gas may be cleaned at a somewhat lower temperature. The temperature of the gas and the character of the condensable components entering the still may be regulated by the treatment to which it is subjected during the scrubbing treatment and prior to its use in the distillation operation.

According to this invention the gases are used for distillation while at a temperature as high as 300° C. or 400° C., or even as high as 500° C. or higher, although larger amounts of gases at lower temperatures can be employed for effecting distillation of the tar.

The temperature and amount of the gases used may be regulated according to the distillation which is to be carried out. If tar is to be distilled only to a limited extent, the temperature of the gases used in the distillation need not be as high, or the amount of the gases employed need not be as great as when the tar is to be distilled to a greater extent to produce a harder pitch.

Where maximum conservation of the heat of the gases is desired in the use of coke oven or gas retort gases, the scrubber may be placed upon the block of ovens or retorts, or even upon the collector main for the gases. In the latter case the scrubbing medium, after being used to scrub the gases may be allowed to flow down into the collector main to flush it. The still may be placed upon or adjacent to the block of ovens or retorts. In using other gases a similar relation between the units may be maintained as far as possible.

In the operation of a coke oven the gases produced are not of uniform composition. At the start of the coal distillation process, oils, etc., are liberated from the coal in large quantities and the first gases given off are rich in volatile products. The gases given off during the latter part of the distillation, for example, during the last thirty percent of the operating time under normal conditions, contain a less percentage of condensable constituents than the richer gases given off during the first part of the distillation, and are known as lean gases. The tars contained in the lean gases contain higher percentages of free carbon than do the tars in rich gases. There is in many cases an advantage in using either the rich gases or lean gases separately and after cleaning, in distillation of tar, oils, etc., according to the present invention. For example, lean gases are capable of taking up a greater quantity of oil and other vapors per unit volume than an equivalent amount of a "rich" gas which already contains more volatile constituents than does the lean gas, both gases being at the same temperature; while richer gases contain a larger amount of condensable vapors which admix with the distilled vapors and are condensed therewith.

In order to take advantage of either rich or lean gas separately for use in distillation, the coke oven may be equipped with two collector mains, each of which is adapted to be thrown into communication with the uptake pipe from each of the ovens in the battery to which the collector mains are connected through a system of valves. As an example, during the first of the distillation operation in any one oven, this oven

will be thrown into communication with the collector main which is connected directly with the ordinary by product recovery apparatus. After the distillation has progressed to the point where 5 lean gases are being given off in this oven, it will be thrown into communication with the other collector main which is in communication with the scrubber and still. By the usual rotation of the ovens in a battery of average size there will 10 at all times be a fairly continuous and uniform production of lean gases, so that the quantity and temperature of the gases passing through the scrubber and still will be fairly uniform at all times. Rich gases will, in many cases, be desired 15 for distillation, and can be utilized by my invention.

Carrying out the distillation according to the present invention, the coal distilling gases, after preliminary cleaning at a high temperature, are 20 brought into heat-interchanging relation with the tar to be distilled and are advantageously brought into direct and intimate contact with the tar. This intimate contact of the tar and gases can be effected in various ways, and the distilling 25 operation can be carried out either as a batch operation or as a continuous operation. Tar or pitch to be distilled can, for example, be atomized or sprayed into a current of the hot cleaned gas, thereby bringing the tar or pitch particles into 30 intimate contact with the hot gas and heating these particles to a sufficient temperature to distill off volatile constituents to a greater or less extent. Instead of spraying or atomizing the tar or pitch into a current of hot cleaned gas, a current of the gas may be forced through a body 35 of tar, tar oil or pitch, thereby heating and agitating it and effecting distillation of the desired constituents therefrom, which vaporized constituents are carried by the escaping gases. 40 The distillation can likewise be effected in a counter-current manner, for example, by causing tar or pitch to flow downwardly through a baffle tower or other apparatus in which an upward flow of the hot cleaned gases is effected, so 45 that the downwardly flowing tar or pitch is progressively heated and distilled, or the hot cleaned gases may be passed over the surface of a body of tar or pitch, for instance in a closed tank. In this latter case, it will be desirable, though 50 not essential, to agitate the contents of the tank to keep fresh surfaces exposed to the gases.

The scrubbing may advantageously be effected by the hot tar or pitch residue from the still. The temperature of the scrubbing liquid is regulated 55 so that the temperature of the gases entering the still is that desired for the distillation which is to be accomplished in the still. In order to maintain the gases entering the still at a sufficiently high temperature, it may be desirable 60 at times to pre-heat the scrubbing liquid to a high temperature, e. g., to around 250° or 300° C. or higher. This may be done by passing the liquid in heat-interchanging relation with hot 65 gases resulting from the distillation process or by applying steam or other heat as from combustion gases to the pipes conveying the scrubbing medium to the scrubber. The scrubbing operation can be modified by regulation of the kind 70 of scrubbing medium used and by regulating its temperature. By using a scrubbing medium containing oils that will be volatilized during the scrubbing the degree of enrichment of the gases used for distillation may be regulated. If the 75 scrubbing medium contains no material that will volatilize during the scrubbing operation, the

hot gases will not be enriched. In some cases volatile materials contained in the gases may actually be absorbed by the scrubbing medium, thus reducing the enrichment of the gases as respects condensable oils.

The tar or other material entrained in rich gases contains a lower percentage of free carbon than does that from lean gases. Thus the character of the residue from the scrubber as respects free carbon content can be controlled by using for distillation gases carrying as entrained material that tarry matter containing the appropriate percentage of free carbon.

Depending upon the extent to which the distillation is carried, substantially only the light oils may be removed from the body of material to be distilled leaving a heavy tar or light pitch in the still, or by carrying the distillation further, heavier constituents will be volatilized and subsequently recovered from the gases, and a still 95 heavier pitch will remain as a residue in the still.

The distillation can be accomplished in numerous ways. For example, a large volume of relatively low temperature gases may be used, or 100 a smaller volume of relatively high temperature gases may be used. The material to be distilled may be preheated if desired before being brought into contact with the gases.

The gases escaping from the distilling opera- 105 tion will carry in vapor form the constituents volatilized from the tar, oil or pitch and will contain in addition thereto such of the vapor constituents carried by the gases entering the still as have not been removed by condensation as a 110 result of the cooling produced by contact of the gases with the material being distilled. In the case of hot coke oven gases employed for the distillation of coal tar produced by the coke ovens, the hot gases after the distillation operation will 115 contain uncondensed constituents from the coal distillation as well as vapors driven off from the coal tar during the distillation. By using coal tar produced at the coke oven plant or any tar while it is still hot before it has had opportunity 120 to cool, a saving in heat may be effected.

The gases from the still can be treated for the condensation and recovery of the desirable constituents contained therein as well as for the recovery of ammonia carried thereby. Where only 125 a portion of the gases from the coal carbonization apparatus are passed through the still, those gases which are enriched by passing through the still can be treated in a separate recovery system and the oils condensed therefrom will be a mix- 130 ture of the oil constituents normally in the gases and those added to the gases during the distillation, whereas the condensate from the remainder of the system will contain only the usual coal carbonization products. The gases can, however, 135 be treated in the same recovery system with the remainder of the gases produced by the coal carbonization.

Several stills may be employed in series so that the gases leaving one still will pass through another still in which available heat of the gases may be used for distillation. Fresh tar or pitch may be supplied to each still, or the residue from one still may be fed to another still, in which case it may be desirable that the flow of gases 145 and material to be distilled will be caused to flow countercurrent to one another. The contact between the gases and material to be distilled will cause more or less removal of impurities from the gases in each still, in addition to distillation 150

of the contents of the stills. A tarry oil may be pumped through two or more stills in succession and hot gases, e. g., gases from a coke oven battery may be bubbled up through the contents of each still, the gases being passed through the stills in a direction countercurrent to the flow of the oil through the stills. The first still may serve as a scrubber, or the gases may be cleaned prior to their use for distillation or progressively cleaned as they pass through the stills. The gases leaving the last still will be clean and contain oil vapors which, on cooling, will be obtained as clean oils. The oil will be distilled and a progressively higher boiling residue will remain in each still. The residue taken from the still into which the hottest gases pass may be a heavy tar or pitch. By such a countercurrent flow, the hottest gases are brought into contact with the heated high boiling residue from preceding stills.

In a coke oven plant where several batteries of coke ovens are operated, the rich or lean or total gases from one battery may be cleaned at a high temperature and employed for distilling tar from the other batteries, or a part of the gases from one battery may be so employed. The gases used in the distillation may be only a portion of the gases collected in the collector main and may be taken off one end of the collector main or all the gases passing through the collector main may be utilized, e. g., by taking them off the center-box according to the customary practice. A product other than a coal tar product, can be distilled and the condensable constituents recovered in a separate recovery system without contaminating the balance of the coal tar products produced.

In some cases it may be desired to regulate the character of the residue of distillation or of scrubbing, as respects free carbon content, or as respects type of oil remaining in or added to it. This may to a greater or less extent be accomplished by using rich or lean or intermediate gases for distillation. Rich gases contain tar with a relatively low free carbon content and they contain also oils of lower average boiling point and lower specific gravity than do lean gases. Rich gases contain a greater amount of tar than do lean gases. As the gases get leaner, the amount of tar contained decreases, the percentage of free carbon in the tar increases, the amount of oil contained decreases, and its specific gravity and average boiling point increase. Since in the scrubbing and distillation operations more or less of the tar contained in the gases will be retained in the scrubbing or distillation residue and more or less of the contained heavy oils will be condensed and retained in the residue, the character of the residues may to some extent be controlled by choosing the proper gases for distillation. Such gases may be rich, lean or intermediate gases.

Where the distillation is carried out as a batch operation, for example, by bringing the hot cleaned gases into intimate contact with tar to be distilled, the tar is progressively heated by the hot gases and the lighter constituents are progressively removed therefrom until the distillation has been carried to the desired point, after which the operation can be discontinued, and the residue withdrawn, and the still recharged with further tar to be distilled. In the case of continuous distillation, the operation can be controlled by regulating the time of contact of the tar with the gases, or the intimacy of contact, or the temperature of the gases, or the amount of

the gases, or a combination of these, so that the desired degree of distillation can be effected.

The invention will be further described in connection with the accompanying drawings illustrating several forms of apparatus embodying the invention and adapted for the practice of the process of the invention, but it is intended and will be understood that the invention is illustrated thereby but is not limited thereto.

In the accompanying drawings.

Fig. 1 shows in a somewhat conventional and diagrammatic manner a plan view of a coke oven battery showing apparatus for the distillation of tar by means of the hot cleaned coke oven gases;

Fig. 2 is an enlarged view of the scrubber of Fig. 1;

Fig. 3 is a plan view of a modified form of apparatus in which two collector mains are shown together with separate apparatus for scrubbing the hot gases;

Fig. 4 is an enlarged detail showing in cross-section the relation of the two collector mains of Fig. 3 to each other and the coke oven;

Fig. 5 is an elevation partly in cross-section showing in greater detail the still shown in Fig. 1;

Fig. 6 is a cross-section of the still shown in Fig. 5;

Fig. 7 is a plan view of the still shown in Fig. 5;

Fig. 8 shows a modified form of still which may be substituted for the still shown in the preceding figures; and

Fig. 9 shows another form of still.

In the drawings, part of the coke oven battery is shown at 1, with the usual uptake pipes 2 for the escape of the coke oven gases, and collector main 3 connected with the uptake pipes. The center-box for the collector main is shown at 4. The coke oven gases escape from the collector main and center-box through the cross-over main 5 to the cooling and condensing system indicated conventionally as two condensers 6 and 7. From these condensers, the gases pass through the pipe 8 and the usual tar trap (not shown) to the exhauster 9, and then through the gas outlet pipe 10 to ammonia saturators and benzol scrubbers, or other apparatus (not shown).

In the collector main and goose-necks sprays 11 are provided for regulating the temperature of the gases to a greater or less extent. The liquor admitted to the collector main, which is not volatilized, together with the condensed tar, collects in the center-box 4, while the gases with some entrained tar and liquor and uncondensed vapors pass through the cross-over main 5. The liquor and tar may be drawn off from the center-box 4 through the pipe 12 to the decanter 13. Ammonia liquor is decanted off to the receptacle 14 and tar is drawn off into the tank 15. The liquor and tar may instead or in addition be drawn off through line 12' to decanter not shown.

The gases used for distillation are shown in the drawings as being drawn off from the end of the collector main through the pipe 16, through which they are conducted to the scrubber 17 where they are scrubbed with liquid sprayed through the sprays 18, and after being thus more or less cleaned are passed through the pipe 19 to the still 20. Instead of locating the collector main, scrubber and still in the relation shown, in actual operation they may advantageously be brought closer together. The scrubber and still may be located upon or closely adjacent to the block of ovens. The scrubber may even be situ-

ated upon the collector main with the still placed adjacent thereto upon top of the battery.

The gases from the still may be passed through separate condensing means illustrated in the drawings as condensers 21 and 22 which may be of the usual "wet" type, or the gases may be passed to other condensing means, such as the usual condensing means connected with the cross-over main 5 by being by-passed through 23 and the main 24 to the usual cross-over main 5. The gases are drawn through the still by the exhauster 25. Baffles (not shown) may be provided at the gas outlet from the still to prevent entrainment of non-volatilized contents of the still by the gases.

In the drawings, the condensers 6 and 7 are shown equipped with decanter 30, and the condensers 21 and 22 with a decanter 31. From these decanters ammonia liquor is drawn off into the ammonia liquor storage 32 and tar is drawn off into the tank 33 and oil into tank 34. Two oil fractions may be collected by running the condensate from 21 and 22 to separate decanters. Line 21' is provided to allow this. The second decanter is not shown.

The sprays 11 in the collector main and goose-necks may be supplied with ammonia liquor from any source through the pipe 36 or the pipes 36 and 36' may preferably be supplied with tar from the tank 33. Tar from the collector main after separation of the ammonia liquor may be supplied to the scrubber through the pipe 37 and to the still through the pipe 38. Residue from the still may be supplied by pump 39 to the sprays 18 to be used as a scrubbing medium in the scrubber by line 40 or may be passed to the storage tank 41.

The liquid entering the sprays 18 is passed through heat interchanger 42 in which the temperature of the liquor may be regulated, if desired.

Residue from the scrubber may be withdrawn to the tank 43 from which it may be recirculated through the scrubber by means of pump 45, pipe 34 and the sprays 18 in the scrubber. In some cases it may be desirable to pump the effluent from the scrubber into sprays 11. Pump 45 and lines 44, 36' and 36 provide for this.

Tar from an outside source such as gas-house tar, etc., may be supplied to the sprays in the collector main through the pipes 46, 36' or 36 or to the scrubber through the pipe 47 or to the still through the pipe 48. The liquor passing to the still passes through the heat interchanger 49.

When operating as a continuous process, the coal tar product from one vessel may be supplied directly to another appropriate vessel without first passing to a storage tank.

In their passage from the ovens to the scrubber, and in their passage through the scrubber itself, the treatment of the gases is so regulated that the gases upon leaving the scrubber and entering the still are at a sufficiently high temperature to effect the desired distillation in the still. Although in general the gases pass from the ovens through collecting means, such as a collector main, in which they may be subjected to regulated spraying, such collecting means may be omitted and the gases from several ovens may be passed directly into scrubbing means, located preferably upon the ovens and from there into the still.

If the gases entering the still, still contain entrained impurities, these will be removed, at least to some extent, by the contact of the gases with

the contents of the still. Heavy constituents present as vapors in the gases entering the still may be condensed, while the distillation will cause volatilization of the lighter constituents of the contents of the still, which will be admixed and carried along with the gases from the still, producing an enriched gas. By subjecting the gases escaping from the still to separate cooling and condensation, a relatively clean oil can be directly obtained as in the storage tank 31, while by returning the gases and admixed vapors to the main condensing system the condensable constituents can be recovered, as in the decanter 30, without the need of separate condensing equipment, and the resulting products will be relatively cleaner than those normally obtained.

According to one preferred method of operation several batteries of a coke oven plant, or a portion of the ovens in a coke oven battery are operated in the usual way, that is by spraying the gases in the collector main with ammonia liquor or tar and ammonia liquor and cooling the resulting gases in direct or indirect condensers located over beyond the cross-over main. The drawings illustrate one battery so equipped that the gases from a portion of the ovens may be treated in the usual manner. The gases passing from the ovens to the left of the center-box in Fig. 1 (or by locating the valve 2' to the right of where it is now shown, all the gases from the ovens to the left of the center-box and some of the ovens to the right of the center-box) will be sprayed with ammonia liquor or ammonia liquor and tar from the pipe 36. The gases passing through the cross-over main 5 are sprayed with water or ammonia liquor in the condensers 6 and 7.

Tar such as that thrown down in the collector main by the usual method of spraying operation here described is supplied to the still 20 through the pipe 48. Residue from the still 115 while still hot is supplied to the scrubber through the line 40. In some cases residue from the scrubber may be used to spray the gases from the ovens near that end of the collector main to which the main 16 is connected. This affords a 120 counter-current flow of gases and tar, or oil. The gases in the end of the collector main from which the gases for distillation are taken are, where high temperature gases are required, subjected to minimum cooling in order that the heat 125 of the gases may be utilized in the still and yet the spraying must be sufficient to prevent objectionable deposit of pitch in the collector main.

To prevent formation of objectionable amounts of pitch here the heavy tar or pitch from the scrubber may in some cases be cut back with lighter tar such as some of that which collects in the container 15. Tar from 15 or tar and ammonia liquor or ammonia liquor may be flushed into the end of main through line 37'. Residue 135 from the scrubber may also be flushed in through 37'. In such cases sprays 11 in the main adjacent to offtake line 16 may be shut off. This will prevent undue cooling of the gases going to 16. The balance of the tar drained from the collector 140 main 3, which collects in the container 15 may be utilized in any suitable manner. By separately collecting the residue from that portion of the collector main sprayed or flushed with tar, a desirable soft pitch or heavy tar may be recovered.

By this method of operation oils, which are practically free from impurities entrained in the gases, may be recovered in the tank 34, or by properly adjusting the valves in the gas mains and by-passing the gases from the still around 150

the condensers 21 and 22 and blending them with the gases passing through the cross-over main into the condensers 6 and 7, a product suitable for creosoting purposes may be recovered directly. The product thus obtained will be richer in high boiling oils and contain less free carbon than ordinary tarry oils. This preferred method of operation is flexible so that creosoting compositions of varying properties may be made to meet various specifications.

10. The apparatus shown in Fig. 3 discloses means whereby the richer gases from the coke ovens may be collected separately from the leaner gases by providing two separate collector mains. To a large extent, the parts of Figs. 1 and 3 bearing like numbers correspond. The coke oven battery is indicated by 301 and the uptake pipes by 302. One collector main 303 with center-box 304 gives off coke oven gases through the main 305, which pass to the condensers 306 and 307 and are exhausted by the exhauster 309. A second collector main 380 with center-box 381 is provided with cross-over main 316 leading to the scrubber 317, from which the gases pass through the main 319 into the still 320 and thence through the condensers 321 and 322 to the main 310, or through the by-pass 323 to the main 324 and the condensers 306 and 307.

Although either rich or lean gases may be cleaned and used for the distillation, in the example given, lean gases are utilized. It is intended and is to be understood that the apparatus is equally adapted for utilizing rich gases for distillation and conducting lean gases to the condensers 306 and 307. By proper regulation of the valves 303' and 380' shown in Fig. 4, the gases evolved during the first of the distillation process may be led to the rich collector main 303, whereas the lean gases evolved during the latter part of the distillation, after lighter oils and more volatile products have been driven off, may be collected in the lean collector main 380. Because of the fact that these lean gases are poorer in condensable oils, they are in many cases better adapted for use in distillation, and, therefore, according to one method of operation they are separately collected as in the main 380 and led to the still to be used for distillation, whereas the rich gases are collected in the main 303 and led to condensers in the usual manner. Likewise, if desired, the main 380 may be used as a rich gas main, and the rich gases used for distillation. In some cases this would be desirable.

Whereas the collector main 303 for the richer gases may be operated according to the usual practice, the operation of the lean collector main should be so regulated by adjusting the sprays of tar and/or ammonia liquor as to give only the desired cooling so that the temperature of the lean gases leaving the collector main is sufficiently high, in spite of the loss of heat involved in passing to the still, to effect distillation in the still. The gases are led off from the lean collector main and pass through the valve 382 to the scrubber 317, and the purified gases are led thence through the pipe 319 to the still 320, although in some cases, particularly with very lean gases, it will not be necessary to scrub the gases in 317. The tar, pitch or other residue in the still may be drawn off into the tank 383, from which it may be pumped to storage 384 by the pump 385.

The residues from the two collector mains may be drawn off into one receiver, or they may be drawn off through the two pipes 386 and 387

into the decanters 388 and 389 respectively. From the decanters, the ammonia liquor may be drawn off into the storage tanks 390 and 391 and the tar into the receivers 392 and 393. This tar may be supplied to the still through the pipes 394 and 395 or to the scrubber through the pipes 396 and 397. Pumps are indicated at 398. The liquid supplied to the still passes through the heat interchanger 399 and that supplied to the scrubber passes through the heat interchanger 400. The scrubber may be sprayed with residue from the still through the pipe 401. The residue from the scrubber may be recirculated through the scrubber by pump 409 and line 409'.

By another manner of operating, the tarry oils 90 condensed in 306 to 307, which are drawn off into the decanter 402 from which ammonia is decanted into the receiver 403, may be drawn off into the tank 404 and this may be supplied to the still.

Non-volatilized constituents collecting in the scrubber may be drawn off into the tank 407, from which they may be drawn through the pipe 408 to any suitable storage, or they may be supplied by the pump 409 through the pipe 410 to the 100 still.

Tar or oil from any part of the system or from outside sources may be used for spraying either or both the collector mains, either alone or with an admixture or ammonia liquor, or ammonia liquor alone may be used for spraying either or both of the collector mains. When the collector main 380 is to be sprayed with tar and the collector main 303 is to be sprayed with ammonia liquor, the tar may be supplied through the line 406'. If it be desired to supply to the still 320 gases at very high temperatures, sprays may be cut off of the main 380 and tar and/or ammonia liquor or oil, etc., may be flushed into the 110 ends of the main through lines 370' and 381'. Accumulation of pitch on the bottom of the main is avoided, and the gases are not cooled to such an extent as they would be cooled were the sprays functioning.

Figs. 5, 6 and 7 show in greater detail the construction of the still 20. The hot gases enter the still by the pipe 19 and are passed out through perforations in the pipe 50 and thereby brought into intimate contact with the contents 125 of the still. The operation of the still may be carried out as a batch operation or it may be made continuous by adjusting the valve 51 to regulate the quantity of liquor admitted through the pipe 52, and by regulating the valve 53 to 130 regulate the quantity of residue withdrawn through the pipe 54. The operation of the still may be so controlled as to produce a heavy pitch threin or by limiting the distillation, a lighter pitch or tar may be formed in the still.

The still 20 may be replaced by a tower such as those illustrated in Figs. 8 and 9 of the drawings wherein the tar or pitch may be passed countercurrent to the hot gases. In Fig. 8, the tar or pitch is supplied through pipe 60 and in passing 140 down over the baffles 61 it is brought into intimate contact with the hot gases admitted through the pipe 62, and the desired constituents of the tar or pitch are volatilized and carried off by the exit gases at 63. Non-volatilized constituents may be drawn off through the pipe 64 or may be recirculated through the pipe 65 by the pump, 66.

In Fig. 9, the gases enter through pipe 70 and in ascending through the tower are sprayed 150

with tar or pitch by means of sprays 71. Baffles 72 are provided for removing a large portion of the entrained spray from the gases which leave the tower by the pipe 73. Non-volatilized constituents collect in the bottom of the tower and may be drawn off through the pipe 74 or may be recirculated by the pump 75 through the pipe 76 and again sprayed into the gases through the sprays 71. Instead of recirculating the tar or 10 pitch, the nozzles may be supplied with fresh tar or pitch through the pipe 78. Other types of stills, in which the gases and liquor are brought into intimate contact, may be substituted for the still 20 of Fig. 1 or still 320 of Fig. 3.

15 The amount of distillation which takes place within the still will depend upon the quantity and temperature of the tar and gases supplied to the still and upon the character of the product to be distilled. The hot coke oven gases for the still 20 may be drawn off from the end of the collector main or at the center box as shown in the drawings, or from any other part of the collector main or other collecting means, or the hot gases may 25 be tapped off any other part of the apparatus from which gases of sufficient temperature may be obtained. If spraying is eliminated or kept at a minimum in one portion of the collector main, and gases from that portion of the collector main are led to the scrubber and then to the still, 30 these gases may be at a temperature not greatly below that at which the gases leave the coke ovens. Scrubbing with tar or oil in the scrubber may tend to reduce the temperature of the gases, but by preheating the scrubbing medium or by using a hot scrubbing medium deficient in volatile oils, or by regulating the quantity of the scrubbing medium, the drop in temperature may be reduced or regulated.

40 Although the operation has been described and shown as a method of removing hot gases from the collector main of a Semet-Solvay coke oven collector main, and scrubbing the gases at high temperature and using them for distillation purposes, it is to be understood that the operation 45 may be adapted to coke ovens of other types and that all the gases from a coke oven battery may be so utilized instead of withdrawing only a part of the gases as in the method here described in detail.

Tars or pitches of various grades may be used 50 as a scrubbing medium and, by distilling in the still, other tars or pitches than those recovered from the hot gases used for distillation purposes, composite heavy tars or pitches will be recovered

in the still and composite oils will be recovered on condensing the vapors leaving the still.

It is to be understood that although none of the equipment is shown as insulated, insulation will be used where it is desired to regulate or 80 largely prevent loss of heat from gas lines, mains, scrubbers, stills, etc. By insulating the apparatus through which the gases pass, they can be maintained at a high temperature not only in the collector main but also in the scrubber and 85 in the still where they are used for distillation after scrubbing.

I claim:

1. The process of distilling heavy hydrocarbon material in liquid form which comprises removing entrained impurities from hot fresh coal gasification gases, bringing the hot treated gases and the material to be distilled into direct contact while the material is maintained at a distillation temperature, the removal of the entrained impurities from the gases being effected 90 at such a high temperature that the treated gases are at a temperature above the distillation temperature of the material when brought into contact with the material so that heat is supplied 95 to the material from the gases.

2. The process of distilling tar which comprises removing entrained pitch particles from fresh hot coke oven gases resulting from the distillation of coal in a coke oven and supplying 105 heat to the tar while the tar is at a distillation temperature by bringing the treated gases into direct contact with the tar, the entrained pitch particles being removed from the gases at such 110 a high temperature that when the gases are subsequently brought into contact with the tar they are above the distillation temperature of the tar, and then cooling the gases and vapors resulting from the distillation of the tar to recover distillate comprising constituents distilled from the 115 tar and constituents originally present in the hot coke oven gases.

3. A process for distilling coal tar hydrocarbons in liquid form which comprises removing entrained impurities from hot fresh coal distillation 120 gases, and bringing the hot treated gases and material to be distilled into direct contact while the material is maintained at a distillation temperature, the removal of the entrained impurities from the gases being effected at such a high temperature 125 that the treated gases are at a temperature above about 300° C. when brought into contact with the material and heat is supplied to the material from the gases.
